UNITED STATES PATENT OFFICE.

ELMER M. COBB AND EUGENE A. SPAULDING, OF PORTLAND, MAINE.

MACHINIST'S V-BLOCK.

SPECIFICATION forming part of Letters Patent No. 709,873, dated September 30, 1902.

Application filed December 19, 1901. Serial No. 86,484. (No model.)

To all whom it may concern:

Be it known that we, ELMER M. COBB and EUGENE A. SPAULDING, citizens of the United States of America, and residents of Portland, 5 Cumberland county, State of Maine, have invented certain new and useful Improvements in Machinists' V-Blocks, of which the following is a specification.

Our invention relates to V-blocks such as 10 are used by machinists for drilling and otherwise working round or hexagonal rods, &c. Such blocks are now made in a single piece, and it often happens that it is desired to support a piece of work too long for a single block.

15 The object of our invention is to construct a V-block which will be adapted to working all diameters which are commonly used in machine-shops and which may be extended to support various lengths. To this end we 20 form our tool of a pair of V-blocks having the notches in line with each other, connecting them by means of one or more guides, upon which one of the blocks is adapted to slide, so that the distance between them may 25 be increased or diminished at will.

We have illustrated our invention by means of the accompanying drawings, in which—

Figure 1 is a perspective view of our device, and Fig. 2 is a cross-section through one of the 30 blocks.

A and B represent two V-blocks, having on one side large notches *d* and on the opposite side smaller notches *e* and *f* to accommodate various diameters. The block A is provided 35 with a vertical hole *a* to provide a clearance

for the drill after it passes through the work. The two blocks are so disposed that their notches will be in exact line with each other and so that they may both be used for supporting the same rod, and they are connected 40 by means of one or more guide-rods *C*, so that one may be made to slide along the rod toward and away from the other. As here shown, the rods are rigidly secured to the block A while they pass through the block 45 B, so as to slide thereon. A screw *c* is provided for the end of one of the rods for a stop, so that the block B may be pulled out to the end of the rods *C* without slipping off.

The device as made forms a machinist's tool 50 which may be easily packed in a tool-chest and which may be used for all sizes of work which are likely to be drilled in a machine-shop. The tool may be expanded and contracted to support work of various lengths, 55 and it is a valuable tool for machinists' use.

We claim—

The herein-described machinist's tool consisting of a pair of V-blocks having their notches in line with each other, and a pair 60 of guide-rods secured to one of said blocks and passing through the other block and upon which it is adapted to slide.

Signed at Portland, Maine, this 14th day of December, 1901.

ELMER M. COBB.

EUGENE A. SPAULDING.
